UNITED STATES PATENT OFFICE.

WILLIAM H. HEULINGS, JR., OF PHILADELPHIA, AND WARREN M. SMITH, OF MOORES, PENNSYLVANIA, ASSIGNORS TO THE J. G. BRILL COMPANY, OF PHILADELPHIA, PENNSYLVANIA, A CORPORATION OF PENNSYLVANIA.

CAR-BODY.

No. 902,402.

Specification of Letters Patent.

Patented Oct. 27, 1908.

Application filed April 17, 1908. Serial No. 427,611.

To all whom it may concern:

Be it known that we, WILLIAM H. HEULINGS, Jr., and WARREN M. SMITH, citizens of the United States, residing in Philadelphia, Pennsylvania, and Moores, Pennsylvania, respectively, have invented certain Improvements in Car-Bodies, of which the following is a specification.

Our invention relates to certain improvements in the construction of cars of the suburban type used particularly upon electric railways.

One object of our invention is to so construct a car that large window openings may be provided without detracting from the appearance of the car and without weakening the construction.

A further object of the invention is to so arrange the window openings that they can be ornamented to give a rich effect without impairing the view through the window of persons standing in the aisle of the car.

These objects we attain in the following manner, reference being had to the accompanying drawing, in which:

Figure 1, is a side view of a portion of a suburban trolley car illustrating our invention; Fig. 2, is a vertical sectional view on the line 2—2, Fig. 1; and Fig. 3, is a sectional plan view on the line 3—3, Fig. 1.

It has been the endeavor in designing large suburban cars to group the windows in pairs and to extend an ornamental glass panel across the top of the windows of each pair, but in doing this the upper portions of the windows have been sacrificed so as to limit the clear space of the windows to the lower portions thereof, thus obstructing the view of persons standing in the car and also weakening the construction to a certain extent.

By our invention, we are enabled to make a window with a large clear space having an ornamental glazed window sash above and allowing for the full height of the window, so that the view of persons standing in the car is not obstructed; the ornamental effect being gained without sacrificing the clear light of the window.

A is the body of the car having vertical window posts B, B', spaced a given distance apart to form the window openings C.

B² is the lower side panel extending from the bottom of the car up to the window sills b.

D is a frame so proportioned as to inclose a 55 pair of window openings.

The window posts B, B form the sides of the window frame and the window posts B' extend through the frame, dividing it into two parts.

The window opening proper extends from the sill b to the lower edge d of a transverse fixed sash E. The post B' is offset at d' so as to form a rest for the sash E and to allow the sash to extend from one side of the window frame to the other, giving the broad effect illustrated in Fig. 1. Back of the fixed sash E is the letter board a extending the full length of the car, and this board forms part of the upper portion A' of the frame of 70 the car.

The glazing of the sash E is preferably of opaque leaded glass so as to hide from view the letter board which is directly back of it, although the glazing may be made of any 75 material and the board protected in any manner. This arrangement of the window frame gives the appearance of a very broad and high frame and consequently adds to the beauty of the car.

In each window opening C, C are two sashes; a lower sash c and an upper sash c'. The upper sash c' in the present instance is fixed and extends back of the fixed sash E and the upper member c² of the frame of this 85 sash is comparatively heavy and is hidden from view by the said fixed sash E and its opaque glazing. The sash c can be raised and is adapted to guideways a' in the window posts B, B'. The portion of the window post B' back of the sash E is also hidden by the opaque glass of the sash E.

The eaves molding i of the roof I is very close to the upper curved portion d² of the frame D, but this does not detract from the 95 ornamental effect of the construction.

By the above arrangement a person standing in the car can readily see through the upper sash and when the lower sash is raised the clear opening is very large, as the lower 100 sash c is allowed to pass back of both the upper sash c' and the fixed sash E and the letter board. By making a solid back for the sash E the leaded glass is thoroughly protected and can be supported and is not liable to be 105 injured as is the case where the glass is exposed on both sides.

While we have shown only the lower sash

movable, both sashes may be made to move, and in still other cases a single fixed or movable sash or a triple sash may be used without departing from the main features of our invention, and in each instance the sash may be arranged to rise as described, or lower into a pocket in the side of the car.

It will be seen that in the type of car described we are enabled to increase the window openings without detracting from the general appearance of the car, and we furthermore protect the ornamental upper fixed sash without weakening the construction of the car body.

15 We claim:—

1. The combination in a car body, of a series of window posts arranged a given distance apart, a lower panel section and letter board forming window openings, an upper 20 and lower sash closing the window openings, a frame inclosing a pair of window openings and extending above the upper edge of the window openings, and a fixed sash extending from one side of the frame to the other in 25 the space above the window openings.

2. The combination in a car body, of a series of window posts arranged a given distance apart and forming window openings, an upper and a lower sash for each window 30 opening, a window frame inclosing a pair of window openings, a sash extending from one side of the window frame to the other and over the window openings, the glass of said sash being opaque so as to hide from view the 35 letter board and the extension of the central window post.

3. The combination in a car body, of a series of window posts spaced a given distance apart to form window openings, a panel ex-

tending along the lower portion of the car 40 body, a letter board extending along the upper portion of the car body, a series of frames each inclosing a pair of window openings, the upper portion of the frame being curved, a fixed sash extending from one side of each 45 window frame to the other side thereof and from the upper edge of the window opening to the frame and hiding from view the upper portion of the window posts extending through the center of the frame and also the 50 letter board above the window openings, a fixed upper sash for each window opening, and ways in the posts for the lower sash to slide in, said lower sash being larger than the upper sash.

4. The combination in a car body, of a series of vertical posts extending from the floor to the roof of the car, each alternate post being wider than the other posts, a side panel, a letter board, a window frame extending 60 from the side panel to a point above the lower edge of the letter board and extending from one wide post to another and forming with the narrow posts two window openings, a sash within the upper portion of the frame 65 extending from one edge of the frame to the other in front of the narrow posts and the letter board, and a sash in the two window openings.

In testimony whereof, we have signed our 70 names to this specification, in the presence of two subscribing witnesses.
